Primary Examiner — Andrew Kerr*Assistant Examiner* — Courtney J Clark-Rasheed*(74) Attorney, Agent, or Firm* — Jose Cherson Weissbrot(57) **CLAIM**

The ornamental design for a bottle cap, as shown and described.

DESCRIPTION

FIG. 1 is a front, right, top perspective view of a bottle cap, showing my new design;

FIG. 2 is a rear, left, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom view thereof;

FIG. 9 is an enlarged view of detail 9 in FIG. 1; and,

FIG. 10 is a front, right, top perspective view thereof, in a condition of use.

The dashed broken lines in the figures are for the purposes of illustrating portions of the bottle cap and form no part of the claimed design.

The dash-dot-dash broken lines are for notating enlarged views and form no part of the claimed design.

The dashed broken lines in the FIG. 10 are for the purposes of indicating the usage environment of the bottle cap and form no part of the claimed design.

1 Claim, 10 Drawing Sheets(56)
